US00D769132S

(12) **United States Design Patent** (10) **Patent No.:** **US D769,132 S**
(45) **Date of Patent:** **** Oct. 18, 2016**

(54) **SNACK PACKAGE WITH STACKING FEATURES**

(71) Applicant: **Kraft Foods Group Brands LLC**, Northfield, IL (US)

(72) Inventors: **Muluken Tilahun**, Waunakee, WI (US); **Paris Alexander Edwards Lowitz**, Chicago, IL (US); **Stacy Alycia Thomas Castro**, Chicago, IL (US); **Thad Fisher**, Madison, WI (US); **William Sutter**, Milan, OH (US)

(73) Assignee: **Kraft Foods Group Brands LLC**, Chicago, IL (US)

(**) Term: **14 Years**

(21) Appl. No.: **29/508,481**

(22) Filed: **Nov. 6, 2014**

Related U.S. Application Data

(63) Continuation-in-part of application No. 29/483,281, filed on Feb. 27, 2014, now Pat. No. Des. 750,976.

(51) **LOC (10) Cl.** **09-03**

(52) **U.S. Cl.**

USPC **D9/761; D9/737**

(58) **Field of Classification Search**

USPC D9/707, 761, 762, 737, 748, 749, 754, D9/755, 700, 686, 688, 689, 390, 414, 415, D9/424-427, 430-432, 434, 435, 454, D9/456; D7/553.1-553.7; D24/104, 226, D24/230; 229/406, 164.1; 220/500, 555, 220/631, 657, 659, 904; 206/461; 416/108, 416/110, 119, 122

CPC B65D 1/36; B65D 71/70; B65D 85/78; A23G 9/503

See application file for complete search history.

(57) **CLAIM**

We claim the ornamental design for a snack package with stacking features, as shown.

DESCRIPTION

FIG. 1 is a front perspective view of an embodiment of the claimed design;

FIG. 2 is a top view of the embodiment of FIG. 1;

FIG. 3 is a bottom view of the embodiment of FIG. 1;

FIG. 4 is a front view of the embodiment of FIG. 1;

FIG. 5 is a rear view of the embodiment of FIG. 1;

FIG. 6 is a right side view of the embodiment of FIG. 1; and,

FIG. 7 is a left side view of the embodiment of FIG. 1.

1 Claim, 5 Drawing Sheets
